(57) **CLAIM**

The ornamental design for an oar, as shown and described.

DESCRIPTION

FIG. 1 is a perspective view of my new design for an oar.

FIG. 2 is a cross-section of my design taken through lines 2—2 of FIG. 1.

FIG. 3 is a cross-section of my design taken through lines 3—3 of FIG. 1;

FIG. 4 is a cross-section of my design taken through lines 4—4 of FIG. 1.

FIG. 5 is a cross-section of my design taken through lines 5—5 of FIG. 1.

FIG. 6 is a cross-section of my design taken through lines 6—6 of FIG. 1.

FIG. 7 is a cross-section of my design taken through lines 7—7 of FIG. 1.

FIG. 8 is a perspective view of a second embodiment of my new design for an oar.

FIG. 9 is a cross-section of a second embodiment of my design taken through lines 9—9 of FIG. 8.

FIG. 10 is a cross-section of a second embodiment of my design taken through lines 10—10 of FIG. 8

FIG. 11 is a cross-section of a second embodiment of my design taken through lines 11—11 of FIG. 8.

FIG. 12 is a cross-section of a second embodiment of my design taken through lines 12—12 of FIG. 8.

FIG. 13 is a cross-section of a second embodiment of my design taken through lines 13—13 of FIG. 8; and,

FIG. 14 is a cross-section of a second embodiment of my design taken through lines 14—14 of FIG. 8.
